UNITED STATES PATENT OFFICE.

CHARLES L. MONTROY, OF COAHOMA, MISSISSIPPI.

STARTING DEVICE FOR INTERNAL-COMBUSTION ENGINES.

1,083,457.

Specification of Letters Patent.

Patented Jan. 6, 1914.

Application filed September 27, 1912. Serial No. 722,700.

To all whom it may concern:

Be it known that I, CHARLES L. MONTROY, a citizen of the United States, residing at Coahoma, in the county of Coahoma and 5 State of Mississippi, have invented certain new and useful Improvements in Starting Devices for Internal-Combustion Engines; and I do hereby declare the following to be a full, clear, and exact description of the 10 invention, such as will enable others skilled in the art to which it appertains to make and use the same.

The present invention relates to starting devices for internal combustion engines, and 15 has for its purpose to provide a device of that character for admitting gaseous charges to the several cylinders of the engine in *seriatim* in definite proportions, and which is manually controllable at will. 20 The invention has for its further purpose to provide a device of the character in question which is of simple construction to the end that the parts thereof may be readily assembled and dis-assembled; one which requires no skill in operation; and one wherein 25 the cost of construction is comparatively small.

With these and other objects in view the invention consists in the novel details of 30 construction and combinations of parts more fully hereinafter disclosed and particularly pointed out in the claims.

Referring to the accompanying drawings forming a part of this specification in which 35 like numerals designate like parts in all the views: Figure 1 is a side elevational view of the device and its associated parts as installed on a motor vehicle; Fig. 2 is a longitudinal sectional view of the device with 40 parts in elevation; Fig. 3 is an end elevational view illustrating the valve mechanism of the cylinder tubes; Fig. 4 is an end elevational view of the device for actuating said valves; and Fig. 5 is a longitudinal sectional 45 view of one of said valves.

Referring to the construction in detail, 1 designates the cylinders of a multi-cylinder engine of a vehicle, and 2 is the tank for containing the usual acetylene or prestolite 50 gas, which gas is adapted to be supplied to the cylinders 1 through the medium of a pipe or tube 3, that connects with the tank 2, and distributing pipes 4 leading to the several cylinders, as shown in Fig. 1.

55 The several cylinder pipes or tubes 4 are connected to communicate with the tube 3

through the medium of a casing 5, that is mounted on the dash-board 6 of the vehicle, and which provides a chamber 7. Said casing has screw-threaded connection 8 with a plug 9 that passes through said dash-board, and is mounted thereon through the medium of a plate 10, that is secured by bolts 11, as in the manner illustrated in Fig. 2. Each of the pipes 4 is provided with a coupling 12, that has screw-threaded engagement with the cap 13 that is in turn screw-threaded on the casing 5 and provides the closure for the chamber 7. The coupling section 12 has a constricted opening 14, 70 forming a seat for the ball valve 15, that is normally held seated through the agency of a spring 16, and which is adapted to be unseated through the agency of a pin 17 that is formed with a head 18. The pipe 3 connects with the acetylene tank 2, and has likewise a coupling section 19 that screw-threads in the casing 5, and a valve mechanism similar to that described above is mounted in said coupling section. 75

A valve actuating means consists of a shaft 20 journaled in the plug 9 and having a conical end 21 bearing in a conical seat formed in the plug 22, fitted centrally within the casing cap 13, and at its other end 80 said shaft is provided with a cap 23, that screw-threads on the end of the plug 9 and retains a shaft packing 24, as shown. A hand-turning crank 25 is provided for actuating the shaft. A pair of cam disks 85 26 and 27 are mounted on the shaft 20 within the casing chamber, and are adapted to actuate respectively the pins 17 of the valves through engaging with their respective pin heads 18, as will be understood. 90

The operation of the device is as follows: The several pistons of the engine cylinders are in the various positions of their cycles of operation, and the crank 25 is turned until the cam disk 27 unseats the valve of the pipe 3 when a portion of the gas in the tank 2 is discharged under its maintained pressure into the chamber 7, and simultaneously therewith one of the valves of the pipes 4 is unseated and a portion of the 100 charge is admitted into its respective cylinder. The further turning of the crank 25 operates to unseat the several valves 15 in succession, and in this succession the several cylinders of the engine are charged and 105 ready for ignition. 110

It is obvious that those skilled in the art

may vary the details of construction and arrangement of parts without departing from the spirit of my invention, and therefore I do not wish to be limited to such 5 features except as may be required by the claims.

What I claim is:—

1. A starting device for multi-cylinder internal combustion engines, comprising a casing 10 providing a chamber; tubes connecting said chamber with the cylinders of the engine; a tube connecting said chamber and the source of fuel supply; controlling valves mounted on the tubes within said chamber; 15 a shaft; cam disks mounted on said shaft for unseating said valves; and means for actuating said shaft, substantially as described.

2. A starting device for multi-cylinder internal combustion engines, comprising a casing 20 providing a chamber; tubes connecting said chamber with the cylinders of the engine; a tube connecting said chamber and the source of fuel supply; spring seated valves mounted on said tubes within said 25 chamber; pins adapted for unseating said valves; a shaft; cam disks mounted on said shaft and adapted to engage with and actuate said pins for unseating said valves; and

means for manually actuating said shaft, substantially as described. 30

3. A starting device for multi-cylinder internal combustion engines, comprising a casing providing a chamber; a cap mounted on the casing and providing a closure for the chamber; a plug detachably connected to 35 said casing; tubes connecting the several engine cylinders with the cap of said casing and communicating with the chambers; a tube connecting the casing with the source of fuel supply; valves mounted on said 40 tubes; a shaft journaled in said plug; a pair of cam disks mounted on said shaft, one of said cam disks adapted for engaging with and unseating the valve of the fuel supply pipe, and the other of said cam disks adapted for successively unseating the valves of the cylinder tubes; and means for manually actuating said shaft, substantially as described. 45

In testimony whereof, I affix my signature, in presence of two witnesses. 50

CHARLES L. MONTROY.
